UNITED STATES PATENT OFFICE.

AUGUST W. HIRSCHFELD, OF WEST MERIDEN, ASSIGNOR TO PARKER AND WHIPPLE COMPANY, OF MERIDEN, CONNECTICUT.

DESIGN FOR FIRE-SHOVEL.

Specification forming part of Design No. 7,737, dated September 1, 1874; application filed July 20, 1874.
[Term of Patent 7 years.]

To all whom it may concern:

Be it known that I, AUGUST W. HIRSCHFELD, of West Meriden, in the county of New Haven and State of Connecticut, have invented a new Design for Fire-Shovel; and I do hereby declare the following, when taken in connection with the accompanying drawings and the letters of reference marked thereon, to be a full, clear, and exact description of the same, and which said drawings constitute part of this specification, and represent a front view.

This invention relates to a design for a cast-metal fire-shovel; and consists in the configuration and ornamentation, as shown in the accompanying illustration.

The outline of the blade is substantially common. The upper part, A, of the handle is

of elliptical form; the next section, B, of equal width, with a branch upon each side running down onto the blade. The ornamentation forms a plain border around the handle and down onto the blade, this border inclosing a panel of floriated tracery, all as shown in the illustration.

I claim—

The design for fire-shovel, consisting of the blade, the handle with elliptical section A and parallel section B, and with plain border running down onto the blade, and inclosing a panel of floriated tracery, as shown in the accompanying illustration.

AUGUST W. HIRSCHFELD.
